See Information Disclosure Statement regarding offer for sale less than one year prior to filing of present application. Color copy showing three commercial juicers.

Primary Examiner—Terry A. Wallace
Attorney, Agent, or Firm—Roger S. Dybvig

[57] CLAIM

The ornamental design for juicer, as shown and described.

DESCRIPTION

FIG. 1 is a perspective view as seen from the top, front, and left side of a juicer showing our new design; FIG. 2 is a front elevational view thereof; FIG. 3 is a top plan view thereof; FIG. 4 is a left side elevational view thereof; FIG. 5 is a right side elevational view thereof; FIG. 6 is a rear elevational view thereof; and, FIG. 7 is a bottom plan view thereof. The broken lines in FIGS. 1, 2, and 4 through 7 showing the power cord and feet are used for illustrative purposes only and form no part of the claimed design.
